UNITED STATES PATENT OFFICE.

JERRY S. KORCAK, OF NEW YORK, N. Y.

PLUG.

Application filed November 3, 1924. Serial No. 747,601.

To all whom it may concern:

Be it known that I, JERRY S. KORCAK, a citizen of Czechoslovakia, residing at New York city, in the county of New York and State of New York, have invented new and useful Improvements in Plugs, of which the following is a specification.

This invention relates to improvements in plugs for use in connection with radio receiving apparatus.

The principal object of the invention is the provision of a plug to which two acoustical instruments may be attached, such as a set of head phones, and a loud speaker, for use in connection with a single jack and wherein the instruments are connected in series for simultaneous operation, there also being a means for selectively controlling the instrument so that either may be short circuited while the other is in operation.

Another object is to provide a plug which eliminates objection of inserting the plug of the head phones into the jack when tuning in on a radio receiver, and afterward removing the phone plug and inserting the plug of the loud speaker.

A further object resides in the construction of a plug which is simple in construction, cheap of manufacture and highly efficient for the purpose intended.

With these and other objects in view, the invention resides in certain novel construction and combination and arrangement of parts, the essential features of which are hereinafter fully described, are particularly pointed out in the appended claims, and are illustrated in the accompanying drawing, in which:

Figure 1 is a perspective view of my improved plug.

Figure 2 is a vertical sectional view therethrough.

Figure 3 is a horizontal sectional view on the line 3-3 of Figure 2.

Figure 4 is a vertical transverse sectional view on the line 4-4 of Figure 2.

Figure 5 is a diagrammatic view of my improved plug showing the manner of connecting a pair of acoustical instruments therewith.

Referring more particularly to the drawing, the reference numeral 10 designates my invention in its entirety, and which includes a housing formed of a pair of sections 11 and 12 of suitable insulating material. The sections are hollowed out or recessed to

snugly receive the parts now to be described.

Mounted within the housing is an angular conductor member 13, the lower end of which is formed with a recess or socket 14 of a sufficient depth to receive the tip of a cord leading to an acoustical instrument such as a head phone or loud speaker. The other end of the member is formed with a sleeve or tubular extension 15 for insertion in a jack. It will therefore be seen that the member 13 serves as one side or leg of a circuit when the plug is in co-action with the jacket of a radio receiving set.

A second angular member 16 is provided and the leg of the same is spaced from the leg of the other member for a purpose to be described. The lower end of the member 16 is also formed with a recess or socket 17 for receiving the tip on the free end of a cord of an acoustical instrument. The upper end of the member 16 supports a post 18 which extends through the sleeve 15 and has its end projecting beyond the sleeve to provide a spherical head 19. Insulating washers 20 and 21 are interposed between the head 19 and the sleeve 15, and between the members 13 and 16 respectively, and an insulating collar 22 is arranged between the sleeve 15 and the post 18. The head 19, post 18 and member 16 serve as the other leg or side of the circuit when the plug is inserted its full length into the jack.

Positioned between the members 13 and 16 and spaced therefrom is a block or plate 23 provided with recesses or sockets 24 and 25 for the same purpose as the recesses or sockets 14 and 17. The opposite sides of the block 23 and the outside of the members 13 and 16 are formed with transverse cut-out portions or grooves 26 which communicate with the respective sockets, and seated within the respective grooves 26 are the curved ends 27 on the flat springs 28. When the tips of the cord of the acoustical instruments are inserted in the recesses, the same will force the flat springs out of the recesses, but the springs have sufficient tension to hold the pins in binding engagement with the walls of the recesses to form a perfect contact and to prevent the pins from accidentally dropping from the plug.

A T-shaped switch arm 29 is pivoted to the block 23 as at 30, and is provided with a manipulating knob 31 which extends through an arcuate shaped slot 32 in the section 12 of the housing. The members 13 and

16 are cut-away as at 33 for receiving the cross head of the T-shaped switch arm when the knob is moved to opposite ends of the slot for the purpose now to be described. 5 The switch arm may be formed with an enlarged portion for frictional engagement with the plug and with the respective angular members when the same is moved into contact therewith.

10 In practice, two acoustical instruments may be connected in series by inserting one of the cord pins of each instrument in the respective recesses 14 and 17, and the other two cord pins into the respective recesses 24 and 25. If the angle member 13 in the block and plate 23 are electrically connected by moving the switch arm 29 to cause the head to enter the cut-away portion 33 in the member 13, the instrument connected with the member 13 and the plate 23 will be short circuited as the current would take the course of least resistance through the sleeve 15, member 13, switch arm 29 and into the instrument having its cord pins in the recesses 25 and 17, and then up to the head 19. If however, the switch arm is moved in the opposite direction to bridge the member 16 and plate 23, the instrument having its cord tip in the sockets 17 and 25 will be short circuited as the current would then flow through the post 18, member 16, switch arm 29, into the instrument connected with the sockets 14 and 25, then through the member 13 to the sleeve 15. 35 When the switch arm is in a position so that the knob is midway between the ends of the slot, current will flow through both instruments. It will therefore be seen that two instruments may be arranged in series, for 40 operation simultaneously, or either instrument may be rendered inoperative due to the selective contact switch. If desired, the section 12 of the housing may have suitable indicating indicia thereon for denoting various positions of the switch arm.

The parts 13, 16, 23 and 29 are constructed of brass or other conducting material, but the switch arm is formed of a conductive material of low resistance in order to short 50 circuit the respective parts of the plug.

From the foregoing description, it will be seen that I have provided a plug for radio

receiving apparatus in which a pair of acoustical instruments may be arranged in series, whereby both instruments are capable of operation simultaneously, or either instrument may be rendered inoperative by the operation of a selective switch.

What is claimed as new is:—

1. A plug for use in connection with radio receiving apparatus comprising an insulated casing, a pair of conductor members arranged in spaced relation with said housing, a socket formed in each of said members, a block of conducting material disposed between said members and spaced therefrom, a pair of sockets in said block, and means for selectively bridging the space between said block and said members, said means including a swingingly mounted T-shape arm. 70

2. A plug for use in connection with radio receiving apparatus comprising an insulated casing, a pair of conductor members arranged in spaced relation with said housing, a socket formed in each of said members, a block of conducting material disposed between said members and spaced therefrom, a pair of sockets in said block, and means for selectively bridging the space between said block and said members, said means including a swingingly mounted T-shape arm, a tubular extension formed on one of said members and projecting from said housing, a post on the other of said members extending through said tubular extension and beyond the same, and insulating means between said tubular extension from said post. 85

3. A plug for use in connection with radio receiving apparatus comprising an insulated casing, a pair of conductor members arranged in spaced relation within said housing, a socket formed in each of said members, a block of conducting material disposed between said members and spaced therefrom, a pair of sockets in said block, and means for selectively bridging the space between said block and said members, said means comprising a pivoted switch arm having a manipulating knob extending through a slot in one wall of said housing. 95

In testimony whereof I have affixed my signature.

JERRY S. KORCAK.
